SURFBOARD

Frederick A. Lambach, 1226 S. 109th St.,
Omaha, Nebr. 68144

Filed Oct. 7, 1965, Ser. No. 87,361

Term of patent 14 years

(Cl. D71—1)

FIG. 1 is a top plan view of the surfboard of this invention;

FIG. 2 is a side elevational view of the surfboard;

FIG. 3 is a front elevational view thereof as taken along the lines 3—3 in FIG. 2;

FIG. 4 is a rear elevational view thereof as taken along the lines 4—4 in FIG. 2; and

FIG. 5 is a bottom plan view thereof.

I claim:

The ornamental design for a surfboard, substantially as shown.
